Application August 26, 1939, Serial No. 292,059
In Germany June 30, 1938

3 Claims. (Cl. 179—171)

This invention relates to circuit arrangements in electron tube devices, and more particularly to new and useful means for coupling two tubes in ultra-high frequency operation.

My invention consists in certain features of novelty which will be fully understood from the following description and be pointed out in the appended claims, reference being made to the accompanying drawing, in which

Fig. 1 is a diagram theoretically explanatory of the art, Fig. 2 shows a circuit arrangement explanatory of my invention, while Fig. 3 is a circuit diagram according to this invention.

It is frequently desirable in high and ultra-high frequency multi-stage amplifiers to interconnect two electron discharge tubes of the individual stages through means, such as a voltage divider, which as indicated in the theoretical circuit of Fig. 1, involves a constant voltage ratio of $U_1 : U_2$ at all frequencies to which L, C, and C_2 are tuned. The voltages across the condensers C_1 and C_2 in this figure are proportional to the respective impedances. This ratio is given by the following expression:

$$\frac{U_1}{U_2} = \frac{1}{\omega C_1} \cdot \frac{\omega C_2}{1}$$

which shows that the frequency ω exerts no influence since ω in the numerator cancels ω in the denominator. A variometer L is inserted which in conjunction with condenser C_1 , C_2 tunes the circuit to the operating frequency. As a matter of fact, the plate of the first tube requires a plate potential and the grid of the second tube requires a negative biasing potential in order to provide an operative circuit, which potentials are applied to the respective electrodes through choking coils D_1 and D_2 , respectively, as shown in the Fig. 2. The presence of these coils unbalances the previously mentioned condition, so that by omitting factors which are irrelevant from the present discussion, the voltage ratio may be expressed as follows:

$$\frac{U_1}{U_2} = \frac{1}{\omega C_1} \cdot \frac{jv}{z}$$

in which

$$v = \frac{\omega}{\omega_0} - \frac{\omega_0}{\omega}$$

where ω_0 is 2π times a frequency different from the operating frequency and z defines the im-

pedance. It is thus obvious that the voltage ratio

$$\frac{U_1}{U_2}$$

5 strongly depends upon frequency.

This disadvantage is eliminated according to my invention by the provision of a voltage divider which is independent of frequency and which is so designed that the plate potential choke coil

- 10 D_1 together with the condenser C_1 forms one oscillatory circuit across the tube 1, and the grid potential choke coil D_2 together with the condenser C_2 likewise constitutes an oscillatory circuit across the grid circuit of the second tube 2 as shown in Fig. 3. These two oscillatory circuits by suitable choice of the respective choke coils are tuned to the same frequency ω_0 , which, however, differs from the operating frequency.
- 15 20 If the factor z_1 defines the impedance of C_1 , D_1 , and z_2 designates the impedance C_2 , D_2 the voltage formula will be:

$$\frac{U_1}{U_2} = \frac{z_1 \cdot jv}{jv \cdot z_2}$$

25 and since jv in the numerator cancels jv in the denominator, the frequency independency is restored in the voltage divider.

What is claimed is:

- 30 1. In a circuit arrangement comprising a first and a second electron discharge device, each having an input and an output and adapted to operate at given high and ultra-high frequencies, a voltage divider for coupling the output circuit of the said first discharge device with the input circuit of the said second discharge device and comprising, an oscillatory circuit across the output circuit of the said first tube, a further oscillatory circuit across the input circuit of the said second tube, the said oscillatory circuits being tuned to the same frequency and said frequency being different from the operating frequency, and a series branch interposed between the said oscillatory circuits for tuning the circuit arrangement to the operating frequency.
- 35 40 45 2. A circuit arrangement as defined in claim 1, in which the impedance of one of said oscillatory circuits differs from the impedance of the other of said oscillatory circuits.
- 50 3. A circuit arrangement according to claim 1, in which a choke coil is provided in each oscillatory circuit for tuning the said circuits to the same desired frequency.

ERICH HEINECKE.
